ATTORNEY

UNITED STATES PATENT OFFICE

161,196

TOOTHBRUSH AND TOOTH PASTE TUBE HOLDER OR SIMILAR ARTICLE

Gustave A. Moskowitz, Washington, D. C.

Application September 23, 1949, Serial No. 5,153

Term of patent 14 years

(Cl. D4—3)

To all whom it may concern:

Be it known that I, Gustave A. Moskowitz, a citizen of the United States, residing at Washington, D. C., have invented a new, original, and ornamental Design for Tooth Brush and Tooth Paste Tube Holder or Similar Article, of which the following is a specification, reference being had to the accompanying drawing, forming a part hereof.

Fig. 1 is a perspective view of a tooth brush and tooth paste tube holder or similar article, showing my new design;

Fig. 2 is an end elevational view of same.

I claim:

The ornamental design for a tooth brush and tooth paste tube holder or similar article, substantially as shown.

GUSTAVE A. MOSKOWITZ.
